Specification forming part of Design No. **11,430**, dated September 23, 1879; application filed September 1, 1879.
[Term of patent 3½ years.]

To all whom it may concern:

Be it known that I, WALTER J. GADSBY, of Boston, in the county of Suffolk and State of Massachusetts, have invented a new and original Design for Carpets, of which the following is a specification.

The nature of my design is fully shown in the accompanying photographic illustration, forming a part of this specification.

The design consists of fan-shaped figures A, rectangular figures B, star-shaped figures C, cross-shaped figures D, conventional forms or figures E F G, and small floral spray-work arranged around said figures.

If desired, the floral spray-work and the figures A B C D may constitute the entire design, the figures E F G being omitted or others substituted for them.

I claim—

1. The design for a carpet having the main figures A B C D and floral spray-work, substantially as shown and described.
2. The design for a carpet having the figures A B C D E F G and floral spray-work, substantially as shown and described.

In testimony whereof I have signed my name to this specification in the presence of two subscribing witnesses this 25th day of August, 1879.

WALTER J. GADSBY.
